ORIENTATING AND CARTON FILLING
DEVICE

John A. Lidberg and Austin S. Chandler, Fitchburg, Mass., assignors to The Brown Bag Filling Machine Company, Fitchburg, Mass., a corporation of Massachusetts

Original application December 18, 1931, Serial No. 581,981. Divided and this application June 7, 1935, Serial No. 25,518

2 Claims. (Cl. 198—20)

This application is a division of our application Serial Number 581,981, for Orientating and carton feeding devices, filed December 18, 1931.

The invention relates to article ordering or orientating devices and has for an object to present a new and extremely simple mechanism for effecting the ends in view and which will function in a new way for the presentation of articles in a fixed position at a given point in a conveyor system.

A specific object of the invention is to present an attachment for a bag filling machine, whereby such machine may be inexpensively adapted to use in filling cartons with the same measuring and filling mechanism used on bags.

A further object is to offer a novel orientating device which is adaptable to use in positioning boxes or small articles such as candy tablets, cakes, or other objects and articles to be filled, wrapped or packed. It is also an aim to present a novel form of buffer wheel for use in automatically adjusting boxes and other articles in proper position for entrance to a work station.

Additional objects, advantages and features of invention reside in the construction, arrangement and combination of parts involved in the embodiment of the invention as will be understood from the following description and accompanying drawings, in which

30 Figure 1 is a top view of the orientating device. Figure 2 is a front elevation thereof.

Figure 3 is a vertical sectional section on the line 3—3 of Figure 1.

Figure 4 is a cross section on the line 4—4 of Figure 1.

There is illustrated a portion of the main frame 10 of a standard form of bag filling machine well known in the trade as the Brown bag filling machine, principal details of which are shown 40 in the patent to Cummings, No. 539,171, and others. The standard machine as marketed includes a main shaft 11, which is utilized as the driving means for parts of the present invention.

A frame 16 is provided having legs 89 adapted 45 to set on the same bed as those of the standard machine. On this frame there is mounted a container-receiving conveyor in the form of a very broad endless belt 17 extending from the front of the machine at right angles to the main shaft. This belt is carried upon rollers 18, one 50 of which is shown. The upper reach of the belt moves inwardly, and at its inner part there is mounted closely over this broad belt a diagonal endless belt 20 mounted on vertical right hand 55 and left hand rollers 22 and 21 located at op-

posite sides of the broad belt. The lower edge of the belt 20 rests on or is located closely over the top side of the belt 17. The right hand vertical roller 22 is nearest the charge forming machine, while the left-hand roller 21 is sufficiently distant to position the front reach of the belt 20 in a plane at an angle of approximately 60 degrees to the line of travel of the broad belt. The roller 18 of the belt 17 is driven at its right hand end by spur gears 48—49 from the main 10 shaft 11.

The shaft 47 of the roller 18 at its left end is utilized to drive by bevelled gears a counter shaft 23, and this in turn drives by bevel gears 23' the left hand vertical roller 21 of the diagonal 15 belt 20. The front reach of the belt 20 is backed by an angle plate 92 secured on the frame 16, one flange resting against the belt. By means of a bracket frame 54 an alley belt 24 is mounted on the frame 10 at right angles to the belt 17 and 20 at the right of the latter, its upper reach moving toward the right. The rear wall 25 of the receiving alley 27 projects slightly over the belt 17 and is bevelled and slightly curved toward the alley at the left end so as to lie close to and as nearly 25 in line with the belt 20 as practicable. The front wall 35 of the receiving alley also extends over the belt 17 and is curved away from the belt 20 and alley 27 slightly. On a suitable horizontally slotted plate 36 on the right hand side of 30 the frame 16 there is a step bearing 37 supporting the lower end of a spindle 38 closely adjacent the right hand edge of the belt 17. On the lower part of the spindle over the bearing there is a pulley 39 located immediately above the level of 35 the lower reach of the belt 24 while at the upper extremity of the spindle there is fixed thereon a planiform horizontal friction wheel 40, slightly above the belt 17 and projecting a distance thereover, its periphery spaced from the diagonal belt 40 20 a distance equal to the width of the alley 27, or slightly more. The wheel 40 is projected a short distance horizontally through the lower part of the front wall 35 of the receiving alley 27 at the curved part of the wall, and through a curved extension 35' of the side wall 14 beside the belt 17. The extension 35' serves to form a flared mouth for the alley 27 and is in effect a continuation of the wall 35. The wheel 40 is provided with a friction facing 41 having circumferentially spaced prominences 42 at suitable intervals, these being in the form of arcuate radial enlargements or lobes. The lobes 42 project considerably through the outer part of the extension 35' but as the latter nears the alley 27 it 50 55

approaches more nearly the major radius of the lobes 42, and the latter are clear of the alley 27 shortly after passing beyond the edge of the belt 17. The wheel 40 is driven by a quarter-turn belt 5 43 from a pulley 44 on the shaft 47 of the roller 18, engaged on the pulley 39 so as to rotate the wheel 40 in a counter-clockwise direction, as viewed from above. The friction facing of the wheel is an elastic belt fitted tightly on the periphery of the body of the wheel. The wheel may be a simple circular disc and the belt may have the prominences 42 formed integrally thereon, as shown. The plate 36 is secured by a clamp nut 45 engaged on a stud 46 extending through the 10 slot of the plate and fixed in a plane face of the right side of the frame 16, the plate being thus movable to permit adjustment of the wheel 40 toward and away from the belt 20 and back wall of the alley 27. The shaft 47 has a large gear 20 48 at its inner end and a smaller gear 49 meshed therewith is fixed on the left hand end of the main drive shaft 11.

The alley belt 24 is operated at a more rapid speed than the belt 17, and the diagonal belt 20 25 also operates at a greater lineal speed than the belt 17.

Operation

In operation, the machine being started the 30 receptacles 15 to be filled are received bottoms down on the belt 17 in any order. By this belt they are carried rearwardly and against the belt 20. Striking this they become adjusted with one 35 side flat against the belt 20 and are rapidly carried in this position onto the belt 24 in the receiving alley 27 by reason of the forces frictionally applied by the belts 17 and 20. Some of the receptacles, however, become interposed between the belt 20 and parts of or corners of other receptacles, preventing the latter from passing into flat engagement with the belt 20, and a group 40 in such order will occasionally move laterally toward the alley. Engaging the jigger wheel 40, however, its friction facing will turn the receptacles which engage it, causing them to adjust 45 themselves quickly to the belt 20. As soon as a receptacle is engaged by the wheel 40 and moved substantially toward operative relation to the belt 20, the belt 17 carries it away from the wheel 50 40, so that no further disturbance of the position of the receptacle will be caused by the wheel. In this way all receptacles are quickly aligned with and entered in the alley 27. At the left (Fig. 2), the alley belt 24 passes around a roller 84 journaled in a yoke 85 having a tongue 86 slidably and

adjustably secured in a suitable channel in the top plate 87 of the bracket frame. This top plate and the tongue 86 support the top reach of the belt. The mounting of the outer end of the belt 17 (not shown) may be similar to the mounting of the left end of the belt 24, or otherwise, as discretion dictates. The legs of the frame 16 may be simple plates 88 having foot flanges or a common flange 90 as in Figures 2 and 3. The right hand end of the diagonal belt 20 is carried by a split roller 22 comprising upper and lower sections, and an arm 91 (Fig. 3) is extended from the diagonal angle plate 92 and secured on the spindle 93 of the split roller between the sections of the roller. The other end of this plate 92 15 is secured on top of the frame 16, beyond the left edge of the belt 17. The angle plate just clears the belt 17 and has a vertical flange 94 at its front side lying against the inner side of the belt 20 as a support or buttress for the latter. 20

The invention is applicable to use in filling bottles, or the orientating of cakes or other articles of various kinds to be delivered to any succeeding mechanism. For the various adaptations to which it is suited, various parts may be omitted, 25 and proportions varied as discretion may dictate to meet the particular requirements of each case.

We claim:

1. An orientating device for polygonal receptacles comprising a first endless belt conveyor, 30 a diagonal stock-engaging element extending entirely across the first conveyor, a second conveyor extending at an angle from the first to receive articles from the side of the first conveyor and said diagonal element, a guide alley over 35 the second conveyor arranged to receive and slidably guide receptacles from the first conveyor, a friction wheel mounted beside the alley adjacent the diagonal element having a concentric body portion spaced from the diagonal element 40 and the far side of the alley more than the width of the alley and having projections of a radius to stop short of the diagonal element and far side of the alley a distance equal to the width of the alley, and means to rotate the said wheel. 45

2. The structure of claim 1 in which said wheel is mounted with its concentric body portion beside the path of articles moved by the first belt and its projections movable over said first belt to engage articles on the first belt adjacent said 50 alley and distant from the diagonal element more than the width of said alley.

JOHN A. LIDBERG.

AUSTIN S. CHANDLER.
